UNITED STATES PATENT OFFICE.

JONATHAN PETERSON, OF BROOKLYN, NEW YORK, ASSIGNOR TO COMBINATION MACHINE COMPANY, OF NEW YORK, N. Y., A CORPORATION OF DELAWARE.

CONTAINER AND PACKAGE FOR CIGARETTES, ETC.

Application filed December 22, 1925. Serial No. 76,964.

My invention relates to containers suitable for packaging small quantities of cigarettes or other commodities for pocket carrying or other purposes, and to packages including such containers.

The invention is well exemplified in its adaptation as here shown for cigarette packages, and the description will be confined to that adaptation; and skilled persons will 10 understand variations that may be made, and the advantages of the structure when used for other purposes or commodities.

The general object of the invention, in its adaptation for small cigarette packages, is 15 to provide a container of relatively thin and flexible sheet material, such as paper and thin cardboard, arranged or formed in such a way that the package is substantially stiffer and more protective to the enclosed 20 cigarettes than the ordinary soft pouch package, and is also materially cheaper than the stiff, necked cardboard boxes, generally employed for the higher grade cigarettes, and which also has a very neat and attractive 25 appearance, and especially to provide, in connection with the other features mentioned, various structural and operative advantages, including an easily operable and durable closure formation, and other features 30 sufficiently referred to hereafter.

In the drawing, which shows the container and package adapted for pocket carrying of a small quantity of cigarettes:

Fig. 1 is an obverse plan view of the 35 wrapper blank.

Fig. 2 is a reverse plan of the same, with the inner tray or stiffener positioned above it preparatory to assembling.

Fig. 3 is a plan view of the inner wrapper, which may be included or omitted.

Fig. 4 is a perspective view of the complete container and package with the closure in fully opened position, and with some parts broken away for explanatory purposes.

Fig. 5 is a similar view with the closure members moved somewhat toward closed position.

Fig. 6 shows the closure members moved 45 farther toward closed position.

Fig. 7 is a section at 7-7, Fig. 6.

Fig. 8 shows the complete container and package in fully closed position ready for vending or pocket carrying.

An inner tray or stiffener S, Fig. 2, is provided, in shallow, rectangular box form, with

an open top. This is made from an originally flat blank of thin cardboard or similar material and includes a bottom portion *a*, end walls *b*, front wall *c* and rear wall *d*, which are bent to vertical position, as shown, 60 and there is ordinarily no need for connecting the meeting edges of these walls.

An outer wrapper *W*, Figs. 1 and 2, is also provided, consisting of a paper blank imprinted with indicia *I*, preferably on one 65 side only, which is to constitute mainly the outer face of the completed package. This blank includes a bottom portion *wa*, end portions *wb*, a front wall portion *wc*, and a rear wall portion *wd*, all these corresponding 70 to analogous parts of the tray or stiffener. Extending from the end wall portions are flaps *e* to form parts of the neck or closure structure, and the outer ends of these flaps are formed, for reasons below, with 75 rounded lobes *f* and *g* and an intermediate concave curvature *h*. Extending from the front *wc* is a front neck or closure member *i* having a flap *j* at its outer end and other flaps *k* at its sides, corresponding to end 80 portions of the container. Extending from the rear wall *wd* is a long closure or cover flap *l* including the portions *m*, *n*, *o*, *p* and *q*, for purposes explained below. At the sides of portions *wd* and *m*, corresponding 85 to ends of the container, are flaps *r*. The flaps *k* and *r* are cut at their inner (lower) ends to provide diagonal end formations *s*, *t*, respectively, and the outer (upper) end corners are rounded as at *u*.

The limits of the various blank sections are indicated by dotted lines, which may be understood as explanatory only, or may be crease or score lines to facilitate the folding or bending of the blank. The flaps *e* are 90 desirably scored or creased on diagonal lines *v* and *w* to provide for neck or closure bending.

At any desirable stage of assembly, the wrapper blank may be adhesively coated on 100 its reverse side, as indicated by stippling in Fig. 2. The folding of the various parts of the wrapper may be done at any convenient time. The wrapper may be formed or folded about a former previous to association 105 with the tray or stiffener *S*, or in some cases the stiffener may be folded on a former and the wrapper folded upon and about the stiffener. The order of assembling or folding operations is therefore immaterial.

Flap *l* is folded on line 10 whereupon the portions *n* and *o* are brought into adherent contact, parts *m* and *p* are brought together and may be adhesively secured or otherwise 5 may be left free, and flap *q* overlies a part of wall member *wd* and is secured by the indicated adhesive. This completes the closure or cover flap formation, the movable part of which includes the corresponding portions 10 *m*—*p* and *n*—*o*; or in other words, this flap is of double, reenforced construction with a "solid" smooth, rounded outer edge 10, consisting of the folded integral material, and with somewhat rounded corners 2. Flap *j* 15 is folded on the line 20 and adhesively secured to the adjacent marginal portion of blank section *i*, providing a double, reenforced edge 20, (Fig. 4). The wall members *wb*, *wc* and *wd*, are 20 now folded up in perpendicular relation to the bottom section *wa*, and flaps *k* and *r* are folded and secured on outer faces of the end wall members *wb*, and end closure flaps *e*, as indicated in Fig. 4, and adhesively secured. 25 The upper ends of the flaps *r* preferably match the lobe formations *g*, but the front lobes *f*, preferably extend above the upper ends of flaps *k*. If the stiffener *S* has not been previously incorporated with 30 the wrapper, it is now inserted and secured, and the container is complete and ready for insertion of the commodity, represented in this case by the inner or embryo package *E*, which consists of a number of cigarettes 35 enclosed in an inner wrapper *A*, Fig. 3. This may be of paper, foil or composite foil and paper, and includes a bottom portion *aa*, end wall portions *ab*, front and rear wall portions *ac* and *ad*, and top flaps *af* extending 40 from the end wall portions. This inner wrapper is folded about the cigarettes in an obvious way, with the top flaps uppermost and superposed, and the embryo package is then inserted in the container, as in Fig. 4. 45 The closure neck consisting of the wrapper portions *i*, *e*, and the entire cover flap, is now ready for closing by folding on the horizontal lines coincident with the top of the stiffener and the embryo package there- 50 in, and also on the diagonal fold lines *v*, with simultaneous bending of the cover flap at crease line 4. An intermediate stage of the closing operation is shown in Fig. 5. The free edge 10 of the closure flap is then 55 inserted under the front neck edge 20, as indicated in Fig. 6, and the cover flap pushed down flat and at the same time inserted farther within or beneath the front necked portion *i*, while the end flaps *r* fold down 60 flat and smooth upon the top of the embryo package by reason of the tuck or bellows fold formations provided by the diagonal fold lines *v*.

In the hands of the consumer, the pack- 65 age is opened in an obvious way, and may

be reclosed very easily and quickly by reason of the foldable neck structure with its fold lines or creases, and by the facility afforded by the inwardly projecting lobes *f* for receiving and guiding the free edge of the closure flap and directing its insertion under the front neck edge 20. When the closure is opened, as shown in Fig. 4, it stands practically upright, providing a full and free exposure of and access to the embryo package and so that either of the top flaps *f* thereof may be raised to permit ready removal of one or more cigarettes at a time. In addition to its convenience, the closure formation is very durable, and of attractive appearance on account of the doubled formation of the cover flap and the doubled, reenforced, smooth, rounded edges at 10 and 20, these edges consisting of the integral folded material and being practically proof against tearing or crumpling in the life of the package. The described formation or arrangement of the cover flap also provides for the exposure at the inner side of the package when the closure structure is opened, of indicia *I*¹, which is a portion of the indicia printed on only one side—originally the outside—of the wrapper. In this way economy in printing is secured, and also the advantage of presenting advertising indicia on the inner face of the closure structure.

I claim:

1. A container for cigarettes or other commodities comprising a wrapper folded in substantially box form to fit about a rectangular inner package or commodity, and comprising a lower portion containing the inner package and having at a broad side thereof a circumferential, upstanding, foldable closure-neck, one wall of which has an extension consisting of the doubled wrapper material and adapted to be inserted under the opposite neck wall portion to form a movable closure flap with a doubled, reenforced, smooth free edge, and a stiffener of cardboard or similar substantially stiff sheet material folded in rectangular box formation with open top and arranged with the lower portion of the container to enclose and reinforce or protect the inner package or commodity.

2. A container for cigarettes or other commodities comprising a wrapper folded in substantially box form to fit about a rectangular inner package or commodity, and comprising a lower portion containing the inner package and having at a broad side thereof a circumferential, upstanding, foldable closure-neck, one wall of which has an extension consisting of the doubled wrapper material and adapted to be inserted under the opposite neck wall portion to form a movable closure flap with a doubled, reenforced, smooth free edge, the wrapper blank being imprinted with indicia on its obverse

side and the folded closure flap structure including a part of said indicia exposed to view at the inside of the package when the closure structure is opened.

- 5 3. A package comprising a commodity having an inner wrapper, a stiffener of foldable sheet material of substantial stiffness at least partly enclosing the commodity, and a wrapper in generally rectangular box form 70 enclosing the stiffener and inner package or commodity, said wrapper comprising a main or lower portion having at a broad side thereof a circumferential, upstanding, foldable closure-neck, one wall of which has an 10 extension consisting of the doubled wrapper material and adapted to be inserted under the opposite neck wall portion to form a movable closure flap with a doubled, reinforced, smooth free edge.
- 20 4. A package comprising a commodity having an inner wrapper, a stiffener of foldable sheet material of substantial stiffness at least partly enclosing the commodity, and a wrapper in generally rectangular box form 80 enclosing the stiffener and inner package or commodity, said wrapper comprising a main or lower portion having at a broad side thereof a circumferential, upstanding, foldable closure-neck one wall of which has an 85 extension consisting of the doubled wrapper material and adapted to be inserted under the opposite neck wall portion to form a movable closure flap with a doubled, reinforced, smooth free edge, said opposite 90 wall having a doubled free edge consisting of the integral, folded wrapper blank material, said foldable neck structure including end members adapted to be folded flat down in tuck-fold formation under the closure flap and upon the inner package, and also including lobes projecting beyond said neck wall free edge and adapted to direct the closure flap beneath said edge in the closing operation, the upper blank being imprinted 95 with indicia on its obverse side and the folded closure flap structure including a part of said indicia exposed to view at the inside of the package when the closure structure is open.
- 10 5. A container for commodities formed from a wrapper shaped to enable it to be folded into a substantially box shaped structure including side and end walls of a depth greater than the depth of the commodity to be received in the structure whereby the side and end walls will extend above the commodity, and with wings extending from the ends of the side walls and lapping upon the outer faces of the end walls throughout the height of the side walls, the top portions of the end walls and the wings creased to provide bellows folds when the central parts of said portions and the tops of the side walls are folded in upon each other with said parts beneath, one of the side walls being extended above the end walls and of a width 105 to lap upon the folded top of the other side wall, said extension being adapted to be tucked between the last named side wall and the adjacent folds of the end walls, whereby the wrapper will be self-held in wrapped position, the end walls having rounded lobes extending beyond the free edge of the last named side wall to provide guides for the tucking in of the extension.
- 15 6. A container for commodities formed from a wrapper shaped to enable it to be folded into a substantially box shaped structure including side and end walls of a depth greater than the depth of the commodity to be received in the structure whereby the side and end walls will extend above the commodity, and with wings extending from the ends of the side walls and lapping upon the outer faces of the end walls throughout the height of the side walls, the top portions of the end walls and the wings creased to provide bellows folds when the central parts of said portions and the tops of the side walls are folded in upon each other with said parts beneath, one of the side walls being extended above the end walls and of a width 110 to lap upon the folded top of the other side wall, said extension being adapted to be tucked between the last named side wall and the adjacent folds of the end walls, whereby the wrapper will be self-held in wrapped position, said extension being of double thickness with the two thicknesses integral at the free edge of the flap.
- 20 7. A container for commodities formed from a wrapper shaped to enable it to be folded into a substantially box shaped structure including side and end walls of a depth greater than the depth of the commodity to be received in the structure whereby the side and end walls will extend above the commodity, and with wings extending from the ends of the side walls and lapping upon the outer faces of the end walls throughout the height of the side walls, the top portions of the end walls and the wings creased to provide bellows folds when the central parts of said portions and the tops of the side walls are folded in upon each other with said parts beneath, one of the side walls being extended above the end walls and of a width 115 to lap upon the folded top of the other side wall, said extension being adapted to be tucked between the last named side wall and the adjacent folds of the end walls, whereby the wrapper will be self-held in wrapped position, the end walls having rounded lobes extending beyond the free edge of the last named side wall to provide guides for the tucking in of the extension.
- 25 8. A container for commodities formed from a wrapper shaped to enable it to be folded into a substantially box shaped structure including side and end walls of a depth greater than the depth of the commodity to be received in the structure whereby the side and end walls will extend above the commodity, and with wings extending from the ends of the side walls and lapping upon the outer faces of the end walls throughout the height of the side walls, the top portions of the end walls and the wings creased to provide bellows folds when the central parts of said portions and the tops of the side walls are folded in upon each other with said parts beneath, one of the side walls being extended above the end walls and of a width 120 to lap upon the folded top of the other side wall, said extension being adapted to be tucked between the last named side wall and the adjacent folds of the end walls, whereby the wrapper will be self-held in wrapped position, said extension being of double thickness with the two thicknesses integral at the free edge of the flap.

modity, and with wings extending from the ends of the side walls and lapping upon the outer faces of the end wall throughout the height of the side walls, the top portions of 5 the end walls and the wings creased to provide bellows folds when the central parts of said portions and the tops of the side walls are folded in upon each other with said parts beneath, one of the side walls being 10 extended above the end walls and of a width to lap upon the folded top of the other side wall, said extension being adapted to be tucked between the last named side walls and the adjacent folds of the end walls, whereby 15 the wrapper will be self-held in wrapped position, and a tray of cardboard or the like, arranged within the lower portion of the container to be enclosed by the wrapper.

9. A container for commodities formed 20 from a wrapper shaped to enable it to be folded into a substantially box shaped structure including side and end walls of a depth

greater than the depth of the commodity to be received in the structure, whereby the side and end walls will extend above the commodity, and with wings extending from the ends of one pair of said walls and lapping upon the outer faces of the other pair of said walls, the top portions of the end walls creased to provide bellows folds when the 25 central parts of said portions and the tops of the side walls are folded in upon each other with said parts beneath, one of the side walls being extended above the end walls and of a width to lap the folded top 30 of the other side wall, the wings and the side wall forming between them a tuck at each end of the side wall into which the extension may be tucked to thereby hold the 35 wrapper in wrapped position. 40

Signed at New York, in the county of New York, and State of New York, this 18th day of December A. D., 1925.

JONATHAN PETERSON.
